UNITED STATES PATENT OFFICE.

THOMAS CLIFFORD OLIVER, OF CHARLOTTE, NORTH CAROLINA, ASSIGNOR TO
CHEMICAL CONSTRUCTION COMPANY, OF CHARLOTTE, NORTH CAROLINA.

METHOD OF AND APPARATUS FOR CONCENTRATING ACIDS.

1,195,075.

Specification of Letters Patent. Patented Aug. 15, 1916.

Application filed March 22, 1916. Serial No. 85,933.

To all whom it may concern:

Be it known that I, THOMAS C. OLIVER, a citizen of the United States, residing at Charlotte, in the county of Mecklenburg and State of North Carolina, have invented 5 a new and useful Method of and Apparatus for Concentrating Acids, of which the following is a specification.

This invention relates to a method of and 10 apparatus for concentrating acids by the use of heat, one of the objects of the invention being to provide simple and efficient means for agitating the acid while it is being subjected to heat so that all portions of 15 the acid will thus be acted on and the accumulation of substances upon the bottom of different portions of the apparatus will be prevented.

A further object is to employ apparatus 20 in which the hot gases pass over the agitated acid.

Another object is to utilize a tower in 25 which is absorbed any acid gas which may be driven from other portions of the apparatus by the heat, this tower utilizing that portion of the heat which escapes from other portions of the apparatus.

A still further object is to provide apparatus of this character all parts of which are 30 built into one unit thus to obtain a simple and durable structure at a minimum cost of construction and whereby practically all of the heat is used and the maximum efficiency attained.

35 With the foregoing and other objects in view the invention consists in certain novel details of construction and certain steps in the method of concentrating acids, which will be hereinafter more fully described and 40 pointed out in the claims.

In the accompanying drawings the form of apparatus used in carrying out the improved process, has been illustrated.

Figure 1 is a view partly in side elevation 45 and partly in section of the apparatus. Fig. 2 is a view partly in plan and partly in horizontal section. Fig. 3 is a vertical transverse section, a portion of said section being taken on the line A—B Fig. 1 while 50 the remainder of the section is taken on the line C—D Fig. 1. Fig. 4 is an enlarged section on line E—F Fig. 2.

Referring to the figures by characters of reference 1 designates a foundation of any

suitable construction, the same being preferably arched and provided with transverse tie rods 2. Above the arch may be arranged common bricks denoted at 3 and it is designed to place over this foundation a layer of asphalt 4 on which is arranged a thickness 50 of acid resisting bricks 5 of any preferred construction, said bricks being laid in acid-proof mortar.

Erected over the brick bottom 5 are parallel concentrating flues 6 and 7 each having an arched top which is inclined downwardly and inwardly from the outer end of the flue, as shown at 8 and merges into a substantially horizontal arch 9 extending practically throughout the length of the flue. 70 The walls of each flue are preferably constructed of silica fire brick, as indicated at 10 and erected on these walls are one or more courses of clay fire brick 11 supporting outer courses of acid-resisting bricks laid in 75 acid-proof mortar and which bricks have been indicated at 12, the same extending downwardly outside of the walls 10 and to the brick bottom 5. This arrangement of the bricks has been found in practice to be the 80 most advantageous. As no condensation of acid takes place on the fire bricks, these bricks are not attacked by the acid. They merely have to withstand the action of the hot gases. However, should these hot acid 85 fumes penetrate to the outer layer of bricks and condense on the cool surfaces, it has been found that the outer arches would be destroyed unless they should be made of acid-proof brick. In other words, the acid fumes 90 and hot gases have no corrosive action whatever until sufficiently cool to condense and this does not occur at the temperature to which the fire brick lining is exposed but does occur at the temperature customarily 95 encountered at the outer arch or casing of acid-proof brick.

The walls 10 and bottom 5 are extended outwardly beyond the outer ends of the flues 6 and 7 and said walls 10, together with an 100 upstanding transverse wall 13 cooperate to form a trough 14 extending across the outer ends of the flues and which communicates with said flues through acid ports 15. This trough has a cover 16 preferably of lead. 105 The trough is provided with extensions 17 likewise covered with lead or the like and which can be opened to permit the insertion

of cleaning rods which can thus be directed into the ports 15.

Extending through the end of the trough is an outlet pipe 18 for the acid, that end of the pipe within the trough being upturned as shown particularly in Fig. 4 so that the acid will be maintained at a predetermined level within the trough.

Extending into the trough is an air pipe 19 having branches 20 which extend through the ports 15 and longitudinally for a desired distance within the flues 6 and 7. These pipes are extended along the bottoms of the flues and those portions thereof within the flues are apertured so that jets of air will be free to escape from the pipes and into the acid contained within the flues.

Formed in the end wall of the flues are ports 21 through which gas burners may be extended or, if fuel other than gas or oil is employed, hot products of combustion from a furnace located adjacent the apparatus herein described, can be directed to the ports 21.

25 Erected at that end of the flues remote from the trough 14 is a tower 22 about the base of which is formed a trough 23 communicating with the interior of the tower through ports 24 in the walls of the tower.

30 Spaced arches 25 are erected in the lower portion of the tower, these arches being constructed of acid-proof brick set in acid-proof cement and serving to support a bridge made up of parallel rows of brick, as indicated at 26. This bridge supports a brick checker-work indicated at 27 and above the checker-work is arranged a filling of quartz indicated generally at 28.

35 Man-holes 29 are formed in one wall of the tower in line with the flues 6 and 7, these man-holes being provided with normally closed cover plates 30. By removing the cover plates the bottom of the tower and the adjacent ends of the flues 6 and 7 can be readily cleaned.

40 A gas outlet pipe 31 is provided adjacent the top of the tower and the quartz so located that it will not obstruct the flow of gas through this outlet pipe.

45 In using the apparatus, heat is directed into the outer ends of the flues, either by extending burners into said flues through the ports 21, or by directing hot products of combustion from adjacent furnaces through the ports 21.

50 Acid is sprayed as ordinarily upon the quartz and will trickle therethrough to the bottom of the tower and then flow longitudinally of the flues and out through trough

55 14 and the outlet pipe 18 which serves to conduct the acid to coolers provided therefor. The greatest heat within the flues is adjacent the ports 21 and this heat gradually diminishes toward the tower, practically all of the heat which leaves the flues

being used in the tower for action upon the descending acid. Thus it will be seen that concentration of the acid begins as soon as the acid is discharged into the tower, the heat increasing as the acid approaches the trough 14. The acid is kept in a high state of agitation by air under pressure which is discharged through the apertures in the pipes 20 so that the accumulation of substances in the concentrating flues is prevented and all portions of the acid in the flues is presented for direct contact with the hot gases. Consequently the concentration is effected quickly. As has been pointed out heretofore the flues can be cleaned by inserting cleaning rods through the extensions 17 and ports 15 and also by opening the man-holes 29. Any acid gas delivered to the tower from the flues will be absorbed within the tower by the downcoming acid which has been sprayed from above.

60 It might be stated that the fire brick lining of each concentrating flue and which lining has been indicated at 11, is not permanently cemented or joined to the acid-proof arch 12 and, consequently, said fire brick lining is free to expand and contract independently of the rest of the arch.

65 It is well known that when sulfuric acid is subjected to a temperature above a certain degree it is disintegrated. It has been found, however, that by following the process herein set forth, gases heated to very high temperatures can be caused to flow over the acid without causing disintegration, this being due to the fact that the acid is kept constantly in a cool condition by the air bubbling through it.

70 What is claimed is:—

1. The herein described method of concentrating acid which consists in subjecting a relatively deep substantially static body of acid to the action of an overlying current of hot gases and directing air through the heated acid to agitate it. 105

2. The herein described method of concentrating acid, which consists in directing hot gases over a relatively deep substantially static body of acid and of forcing air through the acid to agitate it and present 110 all portions of the acid to the action of the heat.

3. The herein described method of concentrating acid, which consists in subjecting a relatively deep substantially static 120 body of acid to heat which increases from one end to the other of said body and in forcing air through the acid where subjected to the greatest degree of heat.

4. The herein described method of concentrating acid, which consists in directing hot gases over a relatively deep substantially static body of acid and thence upwardly between pieces of impervious material, and directing acid downwardly be. 130

tween said pieces of material and into said body, thereby to subject the acid to an increasing degree of heat.

5. The herein described method of concentrating acid, which consists in directing hot gases over a relatively deep substantially static body of acid and thence upwardly between pieces of impervious material, directing acid downwardly through 10 said material and into said body, thereby to subject the acid to an increasing degree of heat, and then directing jets of air through the body of acid to agitate the acid and bring all portions thereof into direct contact with the hot gases thereabove.

6. Apparatus for concentrating acid, including a tower having an arched structure in the bottom thereof, pieces of impervious material supported by the arched structure, 20 a flue opening into the tower for holding a relatively deep substantially static body of acid received from the tower, means for directing hot gases over the acid within the flue and longitudinally of the flue to the 25 bottom portion of the tower, there being a gas outlet adjacent the top of the tower.

7. Apparatus for concentrating acid, including a tower having an arched structure in the bottom thereof, pieces of impervious 30 material supported by the arched structure, a flue opening into the tower for holding a relatively deep substantially static body of acid received from the tower, means for directing hot gases over the acid within the 35 flue and longitudinally of the flue to the bottom portion of the tower, there being a gas outlet adjacent the top of the tower, there being openings adjacent the respective 40 ends of the flue for the reception of cleaning means.

8. Apparatus for use in the concentration of acid, including a tower, an arched structure within the lower portion of the tower, pieces of impervious material supported by the arched structure, flues extending from the bottom portion of the tower and adapted to receive acid from the tower, said flues having acid ports in their outer ends, a transverse trough extending 45 across the outer ends of the flues for the reception of acid from the ports, an outlet member extending from the trough and constituting means for maintaining the acid at a predetermined level within the trough and 50 flues, and means for directing hot gases over the acid within the flues and into the tower.

9. Apparatus for use in the concentration of acid, including a tower, an arched structure within the lower portion of the tower, 60 pieces of impervious material supported by the arched structure, flues extending from the bottom portion of the tower and adapt-

ed to receive acid from the tower, said flues having acid ports in their outer ends, a transverse trough extending across the outer 65 65 ends of the flues for the reception of acid from the ports, an outlet member extending from the trough and constituting means for maintaining the acid at a predetermined level within the trough and flues, and means 70 for directing hot gases over the acid within the flues and into the arched structure in the tower.

10. Apparatus for use in the concentration of acid, including a tower, an arched structure within the lower portion of the tower, pieces of impervious material supported by the arched structure, flues extending from the bottom portion of the tower and adapted to receive acid from the tower, 75 80 said flues having acid ports in their outer ends, a transverse trough extending across the outer ends of the flues for the reception of acid from the ports, an outlet member extending from the trough and constituting 85 means for maintaining the acid at a predetermined level within the trough and flues, means for directing hot gases over the acid within the flues and into the tower, and means for directing air under pressure into 90 the acid within the flues to agitate the acid and present all portions thereof in direct contact with the hot gases thereover.

11. Apparatus for concentrating acid, including an acid concentrating flue, said flue 95 having an arched top comprising an inner thickness of fire brick and an outer thickness of acid proof material, said fire brick being capable of expansion and contraction independently of the acid proof material, 100 means for drawing off acid from the flue, said means operating to maintain the acid at a predetermined level within the flue, and means for directing hot gases over the acid and longitudinally of the flue. 105

12. In acid concentrating apparatus, a concentrating flue having an arched top comprising an inner thickness of fire brick and an outer thickness of acid proof material, said inner thickness being capable of 110 expansion and contraction independently of the outer thickness.

13. The herein described method of concentrating acid, which consists in directing a current of hot gases over a substantially 115 static body of acid, and subjecting the acid to agitation by a cooling medium.

In testimony that I claim the foregoing as my own, I have hereto affixed my signature in the presence of two witnesses.

THOMAS CLIFFORD OLIVER.
